UNITED STATES PATENT OFFICE.

GURDON CONKLING, OF GLENS FALLS, NEW YORK.

JIG FOR SEPARATING ORES.

SPECIFICATION forming part of Letters Patent No. 371,427, dated October 11, 1887

Application filed September 30, 1886. Serial No. 214,998. (No model.)

To all whom it may concern:

Be it known that I, GURDON CONKLING, a citizen of the United States, residing at Glens Falls, in the county of Warren and State of New York, have invented new and useful Improvements in Jigs for Separating Ores, of which the following is a specification.

The object of my invention is to apply to a central discharge-jig means for controlling the quantity of water used in the operation. The peculiar and novel devices and combinations which I use for this purpose are pointed out in the following specification and claims, and illustrated in the accompanying drawings, in which—

Figure 1 represents a vertical central section of a central discharge-jig constructed according to my invention. Fig. 2 is a side view of the dam and gate with discharge-tube in section, the parts being shown on a larger scale than the previous figure. Fig. 2* is another side view of the same. Fig. 3 is a horizontal section of the same in the plane $x x$, Fig. 2. Fig. 4 is a sectional side view of a modification. Fig. 5 is a horizontal section of the same in the plane $y y$, Fig. 4.

Similar letters indicate corresponding parts.

In the drawings, the letter A designates a tub, of wood or other suitable material, in which is placed the jig B. From the bottom of this jig extends the tube C, which is open above and below, and which passes through a stuffing-box, D, secured to the tub A in any desirable manner. In the tube C is firmly secured a cross-shaped step-block, a, in which is fastened the shaft b, that extends to the jig B, which is suspended by means of straps c from a lever, G. The straps c are attached to a sleeve d, which fits the shaft b loosely, but is confined thereon by the collars e e', so that said shaft can turn freely in the sleeve; but if the sleeve is raised or depressed the shaft, together with the jig, must follow. The upper end of the shaft b extends through a bevel-wheel, f, to which it is connected by a feather or key, and said wheel receives a revolving motion by a bevel-wheel, g, mounted on the driving-shaft. The lever G serves to impart to the jig a rising and-falling or jumping motion in a manner well known.

The bottom of the jig is made in the form of

a sieve, the openings of which are of a size suitable to the material to be separated. The ore to be separated is fed into the jig so as to form an ore-bed about equal in depth to the height of the annular flange k, projecting above the sieve, and as the jig receives motion the heavy particles settle down and escape through the meshes of the sieve into the tub, while the light particles, which are the waste, are discharged with the water through the central discharge-tube, C.

The water is introduced into the tub A through a pipe, I, until it rises to a level of three or more inches above the surface of the ore-bed in the jig. Into the flange k of the sieve is fitted the dam l, which is suspended by means of rods m m from a ring-plate, n. This ring-plate turns loosely in a groove formed in a nut, o, which fits a screw-thread on the shaft b. By turning the nut o, therefore, the dam l can be adjusted up or down, according to the depth of water over the ore-bed on the sieve. When the jig is caused to revolve and jump up and down, the waste, together with a quantity of water, is carried over the edge of the dam and down through the tube C, and if the mouth of the dam l is open and unobstructed a very large quantity of water is required to effect the separation of a comparatively small quantity of ore.

For the purpose of controlling the quantity of water which discharges through the mouth of the dam, I combine with said dam a movable gate, p. In the example shown in Figs. 1, 2, 2*, and 3, the movable gate p fits the interior of the dam l, and the dam is made of such a height that its top edge will always be above the level of the water on the ore-bed. In the sides of the dam are openings (one or more) l', and on the upper edge of the dam are formed two inclines, l'', and the gate p is provided with two projections, p', which bear upon the inclines l'', and one or both of which are provided with a set-screw, p'', to hold the gate in any position to which it may be adjusted. The gate, being turned, is raised or lowered, and the openings l' in the dam are uncovered to a greater or less extent. By adjusting the gate in the proper position and securing it in such position by means of the set-screw p'', the discharge of the water through

the openings l' can be regulated. The gate p may, however, be left out, and in this case the dam will be adjusted up and down, so that the openings l' in its sides will be closed more or less by the flange k of the sieve, and the quantity of water which discharges through these openings can thus be regulated.

In the example shown in Figs. 4 and 5 the movable gate p consists of a tube, the diameter of which is equal to that of the dam l , and it is held in position by means of hooks p^3 , which slide up and down on the rods $m m$, and are provided with clamping-nuts p^4 . By adjusting the gate closer to or farther from the top edge of the dam the quantity of water which is permitted to discharge through the dam can be regulated.

By combining with the dam l the movable gate p , I am enabled to work the jig with a greater depth of water above the ore-bed than heretofore, and at the same time the quantity of water which discharges can be controlled, so that no more water is wasted than is absolutely necessary to effect the desired separation.

What I claim as new, and desire to secure 25 by Letters Patent, is—

1. The combination, with a vertical jumping jig having a sieve-bottom and a central discharge, of the vertical annular flange k , rising in the jig around the central discharge, a tubular dam, l , slidable vertically inside of said flange, and means, such as described, for sliding said dam.

2. In a central discharge-jig, the combination, with the dam l , rods m , and means for supporting the same, of a gate, p , hooks p^3 , fitted upon the rods m , screws extending from said hooks through the gate, and clamping-nuts p^4 , substantially as shown and described.

In testimony whereof I have hereunto set 40 my hand in the presence of two subscribing witnesses.

GURDON CONKLING.
